[57] CLAIM

The ornamental design for a telephone handset, as shown and described.

DESCRIPTION

FIG. 1 is a front, receiver-end and side perspective view of a telephone handset showing our new design;

FIG. 2 is a back plan view thereof;

FIG. 3 is a front plan view thereof;

FIG. 4 is a side elevational view of the telephone handset, the opposite side being a mirror-image thereof;

FIG. 5 is a transmitter-end elevational view thereof; and,

FIG. 6 is a receiver-end elevational view thereof.

Fig. 1
